UNITED STATES PATENT OFFICE.

FREDERICK D. GATCHELL, OF NEW YORK, N. Y., ASSIGNOR TO TEXAS COMPANY, A CORPORATION OF TEXAS.

EASY-POUR OIL CAN.

Application filed March 28, 1919. Serial No. 285,840.

To all whom it may concern:

Be it known that I, FREDERICK D. GATCHELL, a citizen of the United States of America, and a resident of New York, New York County, and State of New York, have invented certain new and useful Improvements in Easy-Pour Oil Cans, of which the following is a specification, reference being had to the accompanying drawings, forming 10 a part thereof.

My invention relates to containers for dispensing liquids and has special reference to cans or cartons which are adapted to contain oil and from which the oils are poured 15 out as used.

One object of my invention is to provide a simple and improved can or like container which may be formed of any suitable material such as tin plate, or other metals, or 20 paper, fibre and the like, and shall have a particularly simple and advantageous pouring top or funnel outlet.

A further object is to provide a can of considerable capacity that shall be attractive 25 in appearance, easy to handle, and from which oil or the like may be readily poured as it is used for oiling a machine or the like.

Primarily my thought has been to provide 30 a can which is easy to handle and has for example a capacity of about two quarts which is the ordinary fill for the crank case of an automobile engine. The intention is for the motorist to carry the sealed can 35 with him always ready for use, and when necessary, to supply oil to the engine directly from the can by merely removing the cap and breaking the seal. The top serves as a funnel and my special form of top allows 40 the oil to flow readily and the can to be completely drained when it is held in a substantially horizontal position. There is no necessity of measuring the amount because the can serves as a measure and contains 45 one full charge of an ordinary machine. When empty the can is thrown away and it is never necessary for the motorist to carry a partially filled can with a broken seal from which there is always a possibility 50 of leakage.

In order that my invention may be thoroughly understood I will now proceed to describe the same in the following specification, and will then point out the novel features thereof in appended claims.

Referring to the drawings:

Figure 1 is an elevation with the upper portion broken away and shown in cross section, of a can arranged and constructed in accordance with my invention and constituting an embodiment thereof.

Figure 2 is a plan view of the same can.

The body of the can is designated A which in this embodiment of my invention is in the form of a cylinder which is long relative to 65 its diameter, the diameter being calculated to permit the can to be readily grasped and held in one hand while in use: B designates the spout or top; C the seal which is made of thin sheet metal, and is closed by the oil manufacturer, and is broken by the user; and E designates the cap which is screwed onto the neck or outlet H.

Especial attention is directed to the top B which, instead of being conical or frusto-conical in shape with an axis coincident with the axis of the can, is of a modified conical form having its axis inclined to the base in such a way as to throw the small end or outlet into an eccentric position adjacent 75 to a plane tangent to one edge of the can. The top is so arranged that it acts like a funnel but is more convenient than the usual frusto-conical arrangement because it is easier in many instances to get the outlet 80 close to the opening into which the oil is to be poured even when the can is full and in spite of the fact that the outlet is relatively 85 large so that the oil may flow freely at all times.

The upper end of the funnel shaped top B terminates in an outlet having a peripheral wall of ring-like form. The can is initially filled through this outlet by the manufacturer and is subsequently hermetically closed by means of a piece of thin and soft sheet metal constituting the seal C. This seal is provided with a downwardly 95 extending annular flange which fits closely over the exterior of the ring-like end of the top B and is permanently secured thereto, as by soldering, for instance. The neck portion H is cylindrical in form and its lower end surrounds and closely engages and is permanently fixed to the exterior surface of 100 the annular flange forming an integral part of the seal C. Furthermore, screw threads are provided on the neck portion H to receive the removable cap, or top E, which, when positioned, serves to protect the seal C 105 110

from injury until such time as the contents of the can are to be dispensed by the user.

The can is adapted to be used with relatively thin liquids and can be completely drained if rolled to turn the outlet downward, while held in a substantially horizontal position. While the top is particularly advantageous for use with the can illustrated, my invention is by no means limited to this embodiment, the inventive thought upon which this application is based being broader in scope, and I therefore intend no limitations other than those imposed by the appended claim.

15 What I claim is:

As an article of manufacture, an oil dispensing can for automobile use provided, after being filled, with a puncturable seal that is normally intact, whereby the can can be carried without leakage in an automobile in any random position, and that must be punctured before the contents are dispensed, comprising an elongated cylindrical body of such diameter that it can be con-

veniently grasped by the hand of the user 25 in dispensing the contents, a tapered top of modified frusto-conical form, with its axis inclined relative to the axis of the body of the can and terminating in an eccentrically disposed pouring outlet of ring-like form 30 whereby the can embodies its own funnel of such shape as to facilitate the use of the can in restricted places, a puncturable seal of soft metal capping the outlet and having a downwardly projecting annular flange exteriorly engaging the ring-like portion of the outlet and permanently fixed thereto, a sheet metal cylindrical neck portion, one end of which is fitted exteriorly over the flange of said seal and permanently secured 40 thereto, and a removable top screw threaded upon the open end of said neck portion for protecting the seal while the can is being carried before the seal is punctured for dispensing purposes.

In witness whereof, I have hereunto set my hand this 24th day of March, 1919.

FREDERICK D. GATCHELL.
